STARTING AND RESET GAUGE FOR LOOMS

Boyd O. Bagley, Elmira, N. Y.

Application May 24, 1933, Serial No. 672,686

7 Claims. (Cl. 139—1)

This invention relates to starting and reset gauges for looms and the object of the invention is to provide a gauge which will indicate accurately the force with which the reed strikes the fell of the cloth not only when the loom is started but also when it is necessary to reset the same after the cloth has been loosened in order to remove a fault.

Another object of the invention is to provide a gauge of such construction that its use will assist in avoiding the formation of a "heavy" or a "light" place in the cloth after the removal of a fault.

Another object of the invention is the provision of a gauge which will indicate the proper position of the cloth when starting the loom.

Another object of the invention is the provision of a gauge which will indicate the proper position for the cloth when resetting the cloth after the removal of a fault.

Another object of the invention is the provision of an indicating unit for looms and similar machines which is readily demountable and which is adapted to be mounted on different machines.

Still another object of the invention is the provision of a starting and reset gauge for looms which is simple in construction and positive in operation.

A further object of the invention is the provision of a starting and reset gauge of such construction that it may be readily attached to looms of standard construction without interfering with the operation of the loom and one which does not require modification of any of the parts of the loom.

I attain the above, and other objects of the invention which will be apparent as the description proceeds, by means of the construction shown in the accompanying drawing, in which

Figure 1 is a side elevation of my improved gauge shown in position on a loom of standard construction, the fragmentary parts of the loom illustrated being shown partly in section;

Figure 2 is a perspective of the gauge constituting my invention; and

Figure 3 is a rear elevation of the gauge constituting my invention.

In the drawing, in which like reference characters indicate like parts on all the views thereof, 1 indicates the breast beam of a loom of conventional construction, and 2 indicates the lay beam. 3 indicates the reed carried by the cradle 4 which is positioned in the recess 5 of the lay beam.

The gauge constituting my invention is indicated at 6 and is detachably connected to the lay frame support 7. My improved gauge comprises

an L-shaped metal bracket 8 having an elongated slot 9 through which set screws or bolts 10 pass whereby the gauge may be detachably connected to the lay beam support. It is apparent that the bracket might be provided with a plurality of bolt holes for the screws or bolts 10 instead of the elongated slot 9 if so desired.

The base of the L-shaped bracket 8 is provided with a bearing 11 for the shaft 12, to one extremity of which is secured the arm 13 having an adjusting screw 14, the purpose of which will presently appear.

To the opposite extremity of the shaft 12 is secured an arm 15 preferably of curved formation as shown. The arm 15 carries a knob or button 16 for cooperation with the knob or button 17 of an indicating gauge 18, here shown as of well known construction.

The L-shaped bracket 8 is provided with two recesses 19 in its upper portion, which recesses serve as seats for the indicating gauge 18, the stem of the gauge having a flattened portion which cooperates with a similarly flattened portion in the recesses so that the gauge may be properly positioned in the seat. The support is provided with two recesses in order that the indicating gauge may be located in operative position for either a right hand or a left hand loom.

From an inspection of Figure 1, it will be seen that when the gauge is mounted on the frame and the set screw 14 carried by the arm 13 is adjusted to bear lightly against the cradle 4, the knob or button 16 carried by the arm 15 will extend forwardly and engage the knob or button 17 of the indicating gauge 18. Thus it will be apparent that any movement of the reed cradle will be registered on the indicating gauge.

Both the arm 13 and the arm 15 are so shaped that they will engage the cradle and the indicating gauge respectively. While the arm 13 is here shown as a straight rod, it is obvious that it might be formed with an offset portion at its lower end similar to the offset portion at the upper end of the arm 15, if the loom construction necessitated such formation in order that the gauge cooperate effectively with the cradle and the indicating gauge. It is also apparent that the upper arm might be formed from a straight rod and be provided with a transverse head of such size that it will engage the knob or button on the indicating gauge.

In practice, it may also be desirable to provide a spring or springs for engaging and holding the arms 13 and 15 in their normal positions against the reed cradle and indicating gauge respectively.

in order to prevent their displacement due to loom vibration. Such an additional feature is well within the skill of a mechanic and illustration of such construction is therefore deemed unnecessary.

5 The arms 13 and 15 are here shown as provided with integral sleeves whereby they may be detachably mounted on the shaft 12 and secured thereto by means of set screws. These arms are 10 preferably detachable so that they may be removed, thus permitting of interchangeable arms of suitable formation for either right or left hand looms. It is apparent that if the indicating gauge were seated in the recess shown at the left 15 in Figure 2, the arm 15 should either be replaced by an arm which will engage the indicating gauge button, or the position of the arms 13 and 15 should be reversed and the arm 15 replaced by an arm having an offset of such shape that it will engage the knob or button of the indicating gauge. In the event that the arm 15 is provided with a transverse head, as before referred to, it would engage the indicating gauge button if it were mounted upon the extremity of the 20 shaft in line with the indicating gauge, that is, if the indicating gauge were in the left hand recess, the arm should be mounted on the left hand side of the shaft and vice versa.

30 In operation, when a fault occurs the indicating gauge is inserted in the proper recess 19 of the support so that the knob or button may be engaged by the knob or button on the arm 15; the indication on the gauge is then noted. After the fault has been removed, the cloth is moved 35 until the gauge indicates that the cloth is in its proper position.

40 It is here to be noted that the position of the reed cradle in the recess is determined by the force with which the reed hits the cloth, that is to say, when the lay moves forward carrying the reed, the cradle 4 will not move relatively to the recess 5 until the reed hits the cloth, whereupon this pressure will cause the cradle to move backward out of the recess; it is this movement which will be indicated on the indicating gauge 18. It is obvious that, by using my invention to indicate the movement of the cradle, the reed may be reset to a predetermined position 45 and very accurate adjustment may be made, thereby eliminating any possibility of the formation of either a "heavy" or a "light" place in the cloth.

50 While I have illustrated and described a preferred form of carrying out my invention, it is to be understood that I do not desire to be limited thereby except within the scope of the appended claims.

55 Having thus described my invention, what I claim as new and desire to secure by Letters Patent is:—

60 1. A gauge for looms including an indicating gauge, means for engaging the reed cradle and

means operatively connected to said first-named means for engaging the indicating gauge.

2. A gauge for looms including an indicating gauge, and means whereby it may be mounted on a loom, means for engaging the reed and its cradle, and means operatively connected to said second named means for engaging the indicating gauge. 5

3. A gauge for looms including a support, means whereby the support may be mounted on a loom, 10 means whereby an indicating gauge may be mounted on said support, means on said support for engaging the loom reed and its cradle, and means operatively connected to said last named means and positioned to engage the indicating 15 gauge.

4. A gauge for looms comprising a support, means whereby said support may be mounted upon a loom, means whereby an indicating gauge may be mounted on said support, an arm pivotal- 20 ly mounted on said support and adapted to engage the loom reed and its cradle, and means operatively connected to said arm for engaging and operating the indicating gauge.

5. A gauge for looms comprising a support, 25 means whereby said support may be mounted upon a loom, means for mounting an indicating gauge upon said support, an arm pivotally mounted on said support and adapted to engage said indicating gauge, a second arm pivotally mounted on said support and adapted to engage the reed cradle, and means whereby movement of said second named arm will move said first named arm on its pivot to operate said indicating gauge. 30

35 6. A gauge for indicating the movement of the reed cradle relatively to the lay beam, said gauge comprising a support having means whereby it may be mounted on a loom, means on said support whereby an indicating gauge may be mounted thereon, an arm movably mounted on said support and so constructed and arranged that it will engage the reed cradle, means on said support for operatively engaging the indicating gauge, and cooperating means between said arm 40 and said indicating gauge operating means whereby movement of the former will actuate the latter. 45

50 7. A gauge for indicating the movement of the reed cradle relatively to the lay beam, said gauge comprising a support having means whereby it may be secured to the loom, means on said support whereby an indicating gauge may be mounted thereon, a shaft mounted on said support, an arm secured to said shaft for operatively engaging the indicating gauge, a second arm secured to said shaft and constructed and arranged to rest against the reed cradle, whereby the movement of the reed cradle will be registered on the indicating gauge. 55
